US00D877600S

(12) **United States Design Patent** (10) **Patent No.:** **US D877,600 S**
Chen (45) **Date of Patent:** **** Mar. 10, 2020**

(54) **ROTATIONAL DEVICE**

(71) Applicant: **Xuefeng Chen**, Zengcheng (CN)

(72) Inventor: **Xuefeng Chen**, Zengcheng (CN)

(73) Assignee: **GUANGZHOU
CHANGGONGLANGBO
NETWORK TECHNOLOGY CO.
LTD.**, Zengcheng (CN)

(**) Term: **15 Years**

(21) Appl. No.: **29/630,968**

(22) Filed: **Dec. 26, 2017**

(51) LOC (12) Cl. **08-05**

(52) U.S. Cl.

USPC **D8/373**

(58) **Field of Classification Search**

CLAIM

The ornamental design for a rotational device, as shown and described.

DESCRIPTION

FIG. 1 is a right side, front, top perspective view of a rotational device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
